UNITED STATES PATENT OFFICE.

FRANZ JOSEF MALY, OF AUSSIG, AUSTRIA-HUNGARY.

FORCED-DRAFT FURNACE.

SPECIFICATION forming part of Letters Patent No. 718,779, dated January 20, 1903.
Application filed January 14, 1902. Serial No. 88,779. (No model.)

To all whom it may concern:

Be it known that I, FRANZ JOSEF MALY, a subject of the Emperor of Austria-Hungary, residing at Aussig, Bohemia, Austria-Hungary, have invented certain new and useful improvements in Forced-Draft Furnaces; and I do hereby declare the following to be a full, clear, and exact description of the invention, such as will enable others skilled in the art to

10 which it appertains to make and use the same.

My invention relates to improvements in forced-draft furnaces which are especially adapted for locomotives, but may with the same effect be employed in other movable (for 15 instance, marine boilers) and also stationary boilers.

In the accompanying drawings, which illustrate two different modifications of the invention, Figure 1 is a longitudinal section of the 20 fire-box and the adjacent parts of a locomotive-boiler. Fig. 2 is partly a longitudinal section, partly a side elevation, of the second mode of construction of the furnace. Fig. 3 is a cross-section on the line A B of Fig. 2; and 25 Fig. 4 is another cross-section on the broken line C D, Fig. 2.

Many trials have been made to improve the combustion of fuel in steam-boilers by leading a part of the products of combustion back 30 to the fire; but these trials could not have the expected results, as the manner in which the smoke and eventually the steam mixed therewith were forced into the fire effected for the high amount of heat necessary for the dissociation of the smoke and steam a considerable cooling of the burning fuel on the grate or gas stream rising from it. This cooling of the whole fire, by which the process of combustion became greatly disturbed, and, 35 furthermore, much smoke was produced, shall totally be avoided by the present furnace by leading the back-driven smoke not directly into the fire-box above the fuel, but at first into the ash-pit, where it becomes 40 mixed with the air to be driven through the grate after this air has in such a degree been heated that the fuel must give only a small part of the required dissociation heat of the smoke and steam when the mixture of very 45 hot air, smoke, and steam is streaming through the fuel into the fire-box. For the high temperature of the mixture passing through the

fuel on the grate the burning process of the gases, fresh developed within the fuel and rising from it will not be disturbed, and said 55 mixture of gases after being, during its passing through the layer of fuel, dissociated will again combust with a long flame, and from this whole quantity of entirely-burned gases which now rise up through the fire-box that 60 amount of heat in an innoxious manner—that is, without reducing the economical effect of the furnace—can be taken which is required to highly heat the fresh air to be mingled with the back-driven smoke and the steam, a furnace working in such a manner being particularly suitable for employing anthracite, 65 coke, and other similar fuel, developing, respectively, only small quantities of gas and burning with short flames.

In the annexed drawings, showing furnaces which act in this generally-described improved manner, like letters of reference refer to like parts of construction.

Below the horizontal cylindrical part of the 75 boiler several air-tubes *a* are provided, which feed the fire with the necessary quantity of air, and for this purpose contain steam-nozzles *b*, in the construction of the furnace shown by Fig. 1 this air being led into a respectively large hollow fire-bridge *c*, in which it becomes very highly heated. In order to accomplish this, the fire-bridge has a partition *d*, by which it is divided into two spaces *f* and *e*, of which the former is in open connection with the air-tubes *a* and the latter with the ash-pit *g*. The air sucked by the steam-nozzles *b* into the tubes *a* is forced upward through the space *f*, then downward through the space *e*, from here into the ash-pit, and finally in the well-known manner 80 through the grate *h* and the fuel on the same. The leading back of one part of the smoke from the smoke-box *y* to the ash-pit *g* is effected by means of a tube *i*, the front end of 85 which extends upward to about the center of the smoke-box, (see also Fig. 2,) while the back end projects, as shown in Fig. 1, horizontally into the ash-pit. At a suitable point a steam-nozzle *k* is provided within this smoke-tube *i*. To obtain a better distribution and 90 mixing of the smoke with the air within the ash-pit, a wedge or cone *l* can be located at the mouth of the tube *i*.

The very highly heated mixture of air, smoke, and steam passes through the fuel on the grate *h*, whereby the smoke will at first be reduced to carbonic oxide and the steam dissociated into hydrogen and oxygen, whereupon these gases when passing through the uppermost hot red fuel become again burned to carbonic acid and steam-shaped water—that is, in the present case, to say, overheated steam. These gases, as well as those fresh developed from the fuel, will now in shape of long flames draw through the fire-chamber around the upper edge of the fire-bridge *c* and then through the smoke-tubes *m*, leaving within these latter a larger part of their heat than heretofore, when only short-flamed fuel was employed, without driving back one part of the smoke.

The construction of the present furnace (shown by Figs. 2 to 4) is different from that already described in as far as the fire-bridge has been built up in a modified manner, also the wedge-like part *l* is being replaced by a tube *o*, being across secured to the tube *i* and having a great number of small openings *n*, through which the smoke can enter the ash-pit. The whole fire-bridge, together with its oblique-arranged tong-like upper part, consists of only one casting *c*, being covered with a thin layer of fireproof material *r* and containing three air-channels *p*, each of which being, as shown in Figs. 3 and 4, formed by four shorter channels, through which the air, as indicated by arrows, passes two times up and down, so as to finally enter the ash-pit through the three openings *q*. As these openings *q* are about regularly arranged over the entire breadth of the ash-pit, a good distribution of the smoke and mixing of it with the extremely highly heated air are effected, and the long flames produced in the furnace will rise from the entire surface of the grate. Because the whole quantity of air required by the fuel burning on the grate is forced through the channels *p* the casting forming the fire-bridge *c* is very effectively protected against too early wearing out. Near its upper edge the fire-bridge may be provided with a number of small openings, by means of which a little portion of the hot air in the direction of the arrows *w* directly streams into the flames passing through the fire-chamber.

In employing the present furnace in locomotives it will be useful to extend the blast-pipe up to the upper edge of the funnel of the locomotive to prevent the smoke-box from being, as usual in the common locomotives, evacuated, as such a partial evacuation of the smoke-box would in the present case make it heavier to the steam-nozzles to force the smoke back to the ash-pit. As the air becomes by means of steam-nozzles pressed into the ash-pit, it is not necessary to produce a partial vacuum within the smoke-box, and, furthermore, fuel is also saved for the reason that by dispensing with the vacuum within the smoke-box the steam can in the cylinders

of the locomotive expand to nearly the pressure of the atmosphere.

The gases will in the present furnace leave the smoke-tubes *m* with comparatively high temperature. This can be used for heating the feed-water of the boiler. For this purpose in the smoke-box *y* of the locomotive a spiral tube *z* is provided, the outer end of which is connected with the injector, while the other end will lead the heated water into the boiler. This spiral tube or another similar arrangement may be employed for superheating the steam working in the cylinders of the machine.

What I claim, and desire to protect by Letters Patent, is—

1. In a forced-draft furnace, the combination with a grate, of a hollow bridge-wall having its upper end deflected laterally and projecting over the grate and its interior communicating with the space below the grate, a series of openings in the lower or forward face of said deflected portion of the wall, and means for supplying air to the interior of the deflected portion of said wall.

2. In a forced-draft furnace, a bridge-wall whose upper end is deflected laterally and projects over the grate and which is provided with a series of interior passages each extending throughout the length of the deflected portion of said wall and communicating at one end with an air-supply and at the other end with the space beneath the grate.

3. In a forced-draft furnace, a bridge-wall provided with a series of independent interior passages each communicating at one end with an air-supply and at the other end with the space beneath the furnace-grate, and each of said passages extending laterally over the furnace-grate and being exposed to the direct action of heat arising from fuel on the grate, air entering said passages being compelled to travel throughout the length of the laterally-projecting sections thereof.

4. In a forced-draft furnace, the combination with a grate of a bridge-wall consisting of a series of hollow sections, each having its upper end projecting over the grate, partitions dividing the interior of each of said sections into two passages that communicate at the upper end of the section, one of said passages communicating with the space beneath the furnace-grate, and means for supplying air to the other said passage in each section.

5. In a forced-draft furnace, the combination with a grate, of a bridge-wall consisting of a series of hollow sections arranged side by side, partitions dividing each of said sections into two passages communicating at the upper ends, said sections being arranged in pairs and similar passages in the sections of each pair being connected, at their lower ends, the other passage in one of the sections of each pair communicating with the space below the furnace-grate, and means for supplying air to the corresponding passage in the other section of each pair.

6. In a forced-draft furnace, the combination with a grate, of a hollow bridge-wall having its upper end deflected and projecting over the grate, the interior of said wall being divided into a series of passages, each extending from the lower rear end of the bridge-wall to the top thereof and from said top to the lower front end of the wall, and communicating at said front end with the space beneath the furnace and at an intermediate point of its length with the furnace above the grate, and means for supplying air to the rear end of said passage.

7. In a forced-draft furnace, the combination with a grate, and a series of fire-tubes, of a hollow bridge-wall having its upper end

terminating above the lower plane of the series of fire-tubes and deflected laterally to project over the grate, the interior of said bridge-wall communicating with the space beneath the grate, means for supplying air to the interior of the deflected portion of said bridge-wall, and means for conveying a portion of the products of combustion from beyond the discharge ends of the fire-tubes to the space beneath the furnace-grate.

In testimony whereof I affix my signature in presence of two witnesses.

FRANZ JOSEF MALY.
